(57) **CLAIM**

The ornamental design for a mesh basket, as shown and described herein.

DESCRIPTION

FIG. 1 is a front perspective view of a mesh basket for a straddle-type vehicle, for example and without limitation, an all-terrain vehicle, configured in accordance with a preferred embodiment of the present invention;

FIG. 2 is a front plan view of the mesh basket of FIG. 1;

FIG. 3 is a rear plan view of the mesh basket of FIG. 1;

FIG. 4 is a top view of the mesh basket of FIG. 1;

FIG. 5 is a bottom view of the mesh basket of FIG. 1;

FIG. 6 is a left side view of the mesh basket of FIG. 1; and,

FIG. 7 is a right side view of the mesh basket of FIG. 1.
